(57) **CLAIM**

The ornamental design for a mattress, as shown and described.

DESCRIPTION

FIG. 1 is a perspective view of a mattress, showing our new design; and

FIG. 2 is a front elevational view depicting a foot end of the mattress shown in FIG. 1;

FIG. 3 is a right-side elevational view of the mattress shown in FIG. 1;

FIG. 4 is a left-side elevational view of the mattress shown in FIG. 1;

FIG. 5 is a back elevational view depicting a head end of the mattress shown in FIG. 1; and,

FIG. 6 is a bottom plan view of the mattress shown in FIG. 1.

The broken lines in FIG. 6 indicate portions of the mattress that form no part of the claimed design.

1 Claim, 4 Drawing Sheets
